(57) **CLAIM**

The ornamental design for a stand for television receiver, as shown and described.

DESCRIPTION

1. Stand for television receiver

1.1 is a front perspective view of a stand for TV receiver showing our new design;

1.2 is the front view thereof;

1.3 is the back view thereof;

1.4 is the left side view thereof;

1.5 is the right side view thereof;

1.6 is the top view thereof;

1.7 is the bottom view thereof;

1.8 is another front perspective view showing the stand for television receiver in use.

(Continued)

The broken lines shown in reproduction 1.8 are directed toward environment and form no part of the claimed design.

1 Claim, 8 Drawing Sheets
